UNITED STATES PATENT OFFICE.

HEINRICH BORSARI-FISCHER, OF ZOLLIKON, NEAR ZURICH, SWITZERLAND.

MATERIAL FOR LINING CONCRETE TANKS.

1,152,783.

Specification of Letters Patent.

Patented Sept. 7, 1915.

Application filed September 18, 1912. Serial No. 721,065.

To all whom it may concern:

Be it known that I, HEINRICH BORSARI-FISCHER, engineer, a citizen of the Republic of Switzerland, residing at Zollikon, near Zurich, Switzerland, have invented new and useful Improvements in Materials for Lining Concrete Tanks; and I do hereby declare the following to be a full, clear, and exact description of the invention, such as will enable others skilled in the art to which it appertains to make and use the same.

For the purpose of obtaining an acidproof lining for concrete tanks, frequently acid-proof fusible mixtures of asphalt, paraffin, resins and the like are employed. If such acidproof compounds are to be directly applied to the walls of the concrete tank, while they are still in a fused or plastic condition, it is necessary for the walls to be absolutely dry and they must therefore be previously submitted to a long drying process, as on the one hand dampness will prevent the hot compound from adhering and on the other hand the caustic alkalies contained in the cement will act in a saponifying manner or in other words destroy the liner. It has been suggested, for the purpose of remedying this trouble, to arrange between the acid-proof liner and the concrete wall an insulating intermediate layer of sheet iron, roofing felt, porous substances, stationary air or the like, and such combinations have been employed in form of finished plates or boards with which the tanks were then lined. But this necessitates the use of metallic reinforcements which engage both in the lining material and the concrete, and besides this method has not proved satisfactory in practice. It has further been suggested, for the purpose of obtaining a more secure adhering of the acid proof liner to make the said liner of a porous material bound by cement, and impregnated with the acidproof fusible material. But also this method has the disadvantage, that the acidproof lining material will come in direct contact with the concrete, as the fused material will wholly penetrate the porous veneering layer, which is besides bound by cement, and therefore the said fused material will be destroyed or at least affected by the alkali in the cement, if this cement or the concrete still contains any moisture. All these difficulties are obviated by the present invention by an intermediate layer being arranged between the acidproof liner and

the wall of the tank, which intermediate layer will prevent the moisture from penetrating and is besides alkali proof; besides the use of such layer will obviate the necessity of previously drying out the tank and of employing mechanical fixing means. The lining material may therefore be applied together with the alkali proof intermediate layer directly to the damp walls of the tank, and even be attached to the said wall already during the construction of the concrete tank, whereby besides a great saving in time and labor also a very intimate, close and durable bond between the concrete wall and the liner is obtained. This object is obtained according to the present invention by plates or the like being made of two layers of equal or at least similar physical properties but of different chemical behavior, of which layers the one is composed of an alkali proof mixture of organic, fusible substances, which may, for the purpose of obtaining a greater strength and for reducing the cost, also contain an organic filling material, while the other layer consists of a mixture of acidproof fusible substances, which must on the one hand be able to resist the action of the contents of the tank, and on the other must not affect the same in any way, for instance not give the said contents any smell or flavor. It is, as said hereinbefore, an essential feature, that both layers have the same physical properties, so that an intimate inseparable compound is obtained. For this purpose both layers may contain such substances only, which will be mutually absorbed when in a fused condition or with other words, which may then be mixed.

The drawing represents a transverse section of this duplex lining applied to a concrete wall designed to represent the wall of a tank.

A is the concrete wall and B the plate, consisting of two layers C and D melted together. The layers C and D of the plate have different chemical qualities, in that layer C consists of material that is alkali resisting, while the layer D consists of material that is acid resisting. Their physical properties are however alike or nearly alike so that both materials are firmly connected with one another at the place of contact by melting, and so form a single plate, with which the concrete wall is lined. This lining can be applied by fastening the plate to

the wall after the building thereof by means of mortar or cement, etc., or the concrete wall and lining can, as described, be formed together. These plates are preferably manufactured in the following manner: A highly heated, fused mixture of those substances, which are to form the alkali-proof layer is poured to a suitable thickness on a rolled sand bed, whereby an intimate bond-
age between the grains of sand and the alkali-proof material is obtained. This coating has merely the object to facilitate the bond with the concrete wall, by increasing the surface. It is obvious that the same purpose may also be obtained in any other known manner, for instance by providing a corrugated surface, by recesses, grooves and the like. When these plates have cooled, the acidproof layer is applied by pouring a suitable fused compound of a suitable tem-
perature on it, which will be just sufficient to liquefy the uppermost surface of the first layer, so as to insure an intimate bond through the two layers intermixing at their surface of contact. Naturally the procedure may also be reversed, and the acidproof layer may be first cast whereupon the alkali-proof layer is cast on it. In this case the acidproof layer must, of course, be cast on a smooth surface, and the top surface of the alkali-proof layer must be then pro-
vided with the hereinbefore mentioned corrugations, grooves, recesses and the like. The size of the plates, their thickness and the thickness of the compound plate may be varied according to the respective requirements. Suitable acid and alkali-proof mixtures of organic fusible materials are known; the ratio of the mixtures must, however, to be so chosen, that the two layers have the same stipulated physical properties. So for instance a mixture of asphaltum, gutta-percha and woolfat, freed by

soda lye from the saponifiable components may be used as alkali-proof material, tal-
cum being added as a filling. An acidproof layer, which will bind well thereto is obtained by fusing Manila copal or some other resin with pitch, freed of its components of a low melting point and condensed linseed oil, talcum again being used as a filling. The concrete tanks are lined with the compound plates thus made by said plates being placed into the molds for the concrete wall whereupon the concrete is stamped into the mold; or the plates are secured by means of cement mortar to the finished concrete walls. The joints between the several plates, which are preferably made about $\frac{1}{2}$ in. wide must then be grouted out with the same materials as those of which the plates are composed, and in such a manner that first the alkali-proof layer and then the acidproof layer is poured. By such means a continuous, homogeneous and seamless lining is obtained, which is characterized by consisting of two layers of equal physical properties, of which the one in contact with the concrete wall is alkali-proof, and the other, inner one will resist the attack of the contents of the tank.

I claim:

A concrete tank provided with a lining comprising two layers integrally fused together, the outer layer against the inner wall of the vessel being alkali-proof and united thereto by an alkali material, and the inner layer being acid-proof to resist the attack of the contents of the vessel.

In testimony, that I claim the foregoing as my invention, I have signed my name in presence of two subscribing witnesses.

H. BORSARI-FISCHER.
